RELEASABLE OIL WELL PACKER

James H. Howard, Houston, Tex., assignor to
J. H. McEvoy & Company, Houston, Tex.Application November 24, 1930
Serial No. 497,756

8 Claims. (Cl. 166—10)

My invention relates to packers for use in deep wells for oil, gas, water and the like for the purpose of packing off the space between the liner or screen and the lower end of the casing so as to form a seal at that point.

The most commonly used packers for this purpose are not releasable after they have been set in position in the well. This is particularly true with canvas packers which are most commonly used.

It is an object of my invention to provide a packer which may be readily set in position in the well but which may be thereafter released and withdrawn either with or without the extension upon the liner below the packer.

I contemplate the use with a packer of means which will hold the packer in expanded position when it has once been set but which may be released by rotation with a releasing tool so that the device may be withdrawn.

The invention lies in the particular construction and arrangement of the parts making up my improved packer, the construction and arrangement of which will be apparent from the description which follows.

Referring to the drawing herewith, Fig. 1 is a central longitudinal section through a broken section of liner having my invention employed thereon.

Fig. 2 is a similar view illustrating the lower end of the packer and a portion of the liner, Fig. 2 illustrating, together with Fig. 1, the complete invention.

Figs. 3 and 4 are transverse sections on the planes 3—3 and 4—4 respectively of Fig. 1.

My device is intended to be mounted at the upper end of a liner section 1, the lower end of which is intended to be supported upon the bottom of the well. Said liner section is connected through a lefthand thread 2 with a collar 3 acting to couple the liner section 1 with the packer barrel 4.

The packer barrel serves as a support for a canvas packer 5 of the usual construction. Its lower end is wired at 6 to the corrugated lower end 7 of the barrel. The upper end is wired at 8 to the corrugated lower end of a sleeve 9 having a swivel connection at 10 with the mandrel 12.

The upper end of the packer barrel is formed with a downwardly inclined buttress thread 11, adapted to be engaged by slips 13. The upper end of the packer barrel is engaged with a collar 14, the upper end of which is formed with a coarse lefthand thread 15 for engagement with a tubular member 16.

The tubular member 16 is connected at its upper end by a collar 17 to the setting pipe or stem 18, which is understood as extending upwardly to the surface. The tubular member 16 is divided transversely between its ends and is connected to a nipple 19. Set screws 20 are provided for making this connection a secure one. The adjacent ends of the tubular member are formed with inwardly extending flanges 21 to engage over the reduced ends 22 of the dogs 23. Said dogs are adapted to fit within a recess 24 in the outer periphery of the nipple 19. They are pressed resiliently outward by springs 25 which may be best seen in Fig. 3. The upper end of the nipple 19 has screwed therein a wash plug 26 having a passage 27 therethrough to receive the wash pipe.

The mandrel 12 is formed on its inner face with a tapered seat 28 to receive the slips 13 which are tapered downwardly to engage within said seat. Said slips are separated slightly at their adjacent edges to receive the keys 29, as shown in Fig. 4. This holds the slips nonrotatable relative to the mandrel so that the rotation of the mandrel will cause the rotation of the slips and screw them around upon the thread 11 of the packer barrel. The mandrel is also connected to the collar 14 by means of shear pins 30. These pins normally hold the packer barrel to the mandrel and prevent relative movement of the two parts while going into the hole. The upper end of the mandrel is connected to a pipe 31 extending a short distance above the packer and having a pair of opposite J slots 32 therein. I may provide a spacing or packer member 33 between the upper end of the pipe 31 and the setting pipe 18, as shown.

In the use of my invention the device is assembled as shown in Figs. 1 and 2 before it is introduced into the hole. It is to be understood that under ordinary conditions the casing has already been set in the hole and the liner at the lower end of my device is inserted through the casing and into contact with the bottom of the hole. When in this position the well may be washed in the usual manner by inserting a wash pipe downwardly through the wash plug 27 and when the well has been properly washed the packer may be set.

This is accomplished by unscrewing the setting tool from the collar 14 by a righthand rotation of the tool. When the joint 15 has been unscrewed the setting tool is raised until the dogs 23 are extended outwardly by the springs over the upper end of the pipe 31. A downward thrust of the setting tool upon the pipe 31 will engage the dogs 23 therewith shearing the pins

30 and forcing the mandrel together with the slips 13 downwardly along the packer barrel until the packer has been expanded laterally to close the space between the liner and the casing. 5 When this has been accomplished the dogs 13 will be in engagement with the thread upon the barrel 4 and resist any tendency of the packer to be released from its expanded position. The setting tool may then be withdrawn from the 10 hole.

If it is later desired to withdraw the packer a setting tool with opposite studs or pins thereon may be inserted downwardly with the pins engaging with the J slots 32 of the pipe 31. The 15 pipe may then be rotated together with the mandrel to move the slips 13 rotatably about the packer barrel 4 and screw the slips upwardly along the same. This rotative movement will be accomplished by an upward pull on the tool 20 so as to maintain the slips in engagement with the threads upon the barrel. The swivel joint at 10 will serve to prevent the transmitting of a rotative movement to the packer. As the slips and mandrel travel upwardly along the barrel 25 the packer will be withdrawn from expanded position and when the upper ends of the slips engage with the collar 14 the device may be withdrawn from the hole. If, however, it is found that the lower end of the liner is stuck in the 30 well and can not be withdrawn a further rotative movement will tend to unscrew the tight joint between the collar 3 and the upper end of the liner section 1, thus allowing the packer to be withdrawn, leaving the liner in the hole.

35 The advantages of the construction lie in the simplicity of the device whereby it may not easily get out of order in use. The device is also an economical one which may be supplied to the operator without great expense. The releasing feature 40 is of particular value as it is possible to withdraw the packer in a positive manner either with or without the lower end of the liner.

What I claim is:—

1. A packer for wells including a liner, a packer 45 barrel thereon, a packer on said barrel, a mandrel having a swivel connection with the upper end of said packer, and means on said mandrel engaging said packer barrel to allow downward sliding movement of said mandrel on said barrel, but to 50 prevent upward sliding movement thereof, said means being movable upwardly on said barrel through rotation thereof on said barrel.

2. A packer for wells including a liner, a packer 55 barrel thereon, a packer on said barrel, a mandrel having a swivel connection with the upper end of said packer, and toothed dogs fitting in a tapered recess on said mandrel engaging said packer barrel to allow downward sliding move-

ment of said mandrel on said barrel, but to prevent upward sliding movement thereof.

3. A packer for wells including a tubular member, a packer barrel thereon, a packer on said barrel, a mandrel having a swivel connection with said packer, means whereby said mandrel may be rotated, threads on said barrel and slips on said mandrel engaging said threads adapted to slide downwardly thereon but movable upwardly thereon only through rotation. 80

4. A packer for wells including a tubular member, a packer barrel thereon, a packer on said barrel, a mandrel having a swivel connection with said packer, means whereby said mandrel may be rotated, threads on said barrel and slips on said mandrel engaging said threads adapted to slide downwardly thereon but movable upwardly thereon only through rotation, and means on said mandrel to communicate rotative movement of said slips about said pipe. 90

5. A packer for wells including a liner, a packer barrel having a left-hand-threaded connection therewith, a setting tool having a releasable connection with said barrel, a mandrel connected with said packer, means whereby said mandrel may be rotated, and a longitudinal pull exerted thereon, and means on said mandrel adapted to engage said barrel and resist relative upward movement of said mandrel, said engaging means being movable upwardly on said barrel through 105 rotation of said mandrel.

6. In a packer for wells, a packer barrel, a packer thereon, a mandrel having a swivel connection with said packer, an inner downwardly tapered seat in said mandrel, slips in said seat slidably 110 downwardly with said mandrel on said barrel and rotatable with said mandrel thereon and means to rotate said mandrel and said slips.

7. In a packer for wells, a packer barrel, a packer thereon, a mandrel having a swivel connection 115 with said packer, an inner downwardly tapered seat in said mandrel, slips in said seat slidably downwardly with said mandrel on said barrel and rotatable with said mandrel thereon, said slips being movable upwardly on said barrel only when 120 rotated and pulled upwardly by said mandrel and means to rotate said mandrel and said slips.

8. A packer for wells including a liner, a packer barrel connected therewith, a setting tool having a releasable connection with said barrel, a 125 mandrel movable on said barrel, means whereby said mandrel may be rotated, and a longitudinal pull exerted thereon, and means on said mandrel adapted to engage said barrel and resist relative upward movement of said mandrel, said engaging 130 means being movable upwardly on said barrel through rotation of said mandrel.

JAMES H. HOWARD.
